C. MOUL, OF HANOVER, PENNSYLVANIA.

Letters Patent No. 73,914, dated January 28, 1868.

IMPROVEMENT IN HARVESTERS.

The Schedule referred to in these Letters Patent and making part of the same.

TO ALL WHOM IT MAY CONCERN:

Be it known that I, C. MOUL, of Hanover, in the county of York, and State of Pennsylvania, have invented a new and improved Extensible Shaft for Reaping and Mowing-Machines; and I do hereby declare that the following is a full, clear, and exact description thereof, reference being had to the accompanying drawings, making part of this specification, in which—

Figure 1 is a sectional view of portions of a harvesting-machine, showing one mode of applying my extensible shaft.

Figure 2 is an enlarged longitudinal section through the extensible shaft, contracted in its shortest compass. Figure 3 is a similar view of the shaft fully extended.

Figure 4 is an enlarged cross-section through the three sections of the extensible shaft.

Similar letters of reference indicate corresponding parts in the several figures.

This invention relates to an improvement on extensible shafts, which are particularly designed for harvesting-machines which have their platforms hinged to their draught-frames, the shafts being used for communicating motion to the sickles, the rakes, or reels from driving-machinery on the main frames, and preventing, by their extensibility, the parts from binding and working hard. Hitherto, extensible shafts for the above-mentioned purpose, have been made of two sections, one sliding in and out of the other, which for some purposes are objectionable, as the required length of movement of the parts connected together cannot be obtained.

The nature of my invention consists in a novel manner of constructing an extensible shaft for a harvester, of three or more sections, the three sections being fitted together one within another, and strengthened and guided by tongues and grooves formed on and in the sections, as will be hereinafter described.

By my invention I am enabled to obtain a more compact contrivance when the same is fully contracted, than is the case when the shaft is made of only two sections, and the same fully contracted; for instance, if one of my shafts is made of three sections, each three feet long, and one of the ordinary shafts is made of two sections, each four and a half feet long, it is obvious that in mine the length of the shaft can be reduced, by sliding one section within another, to about three feet, whereas, in the case of the ordinary shaft, the length of the shaft can only be reduced, by sliding one section in the other, to about four and a half feet. The object or benefit secured by providing for reducing the length of a shaft from nine fees to three feet, is this; in the use of the shaft with two sections, I suffered considerable loss from the following cause: in operating the harvesting-machine in the field, the shaft with but two sections was too long, when fully contracted, to allow the hinged platform to come up close enough to the machine or draught-frame, and consequently the gearing would be broken by too great strain; but by adopting a three-part shaft, of the same length, when expanded, as the two-part shaft, this difficulty was fully obviated. Again, with a shaft made of three sections, each four and a half feet long, a much greater sweep can be obtained than with a shaft of two sections, each four and a half feet long, while at the same time the parts of the shaft first named can be as compactly contracted or folded within one another as is the case with the two-part shaft. A long sweep or extension I often have found necessary, for the reason that in some places the two-part shaft, say of nine feet in length when extended, was too short for the movement of the platform on its hinge-joint, and the result was that the sections would unship and the rake stop its operation, and often the disconnected part would become entangled with the wheel or "traveller," and get broken. And finally, to combine both short contraction and long extension in one and the same shaft, is the thing necessary, and by my arrangement of a series of short sections, this end has been attained, for by making a shaft twelve feet in length, out of four sections of three feet each, it is obvious that a much longer extension and a much shorter contraction than is possible with a shaft of nine feet in length, made of but two sections, each of which is four and a half feet long.

To enable others skilled in the art to understand my invention, I will describe its construction and operation.

In the accompanying drawings, A represents one section of the extensible shaft, which is constructed hollow, and provided with ears b upon it, by which it can be coupled to a driving or a driven shaft. B represents another hollow section of the extensible shaft, which is constructed to slide freely but not loosely within the largest section A, and to receive within it a third section, C, which latter may be made solid, and provided with coupling-ears, a, upon its exposed end. I thus have three telescopic sections, which may be contracted into the

short compass shown in fig. 2, or extended, as shown in fig. 3. In cross-section, the three sections, A, B, and C, are rectangular, but they may be made of any other shape which will prevent these from rotating one within another. In order to prevent these sections from being separated by extending them, I form a shoulder or stop, *d*, upon the inner end of the section B, and a shoulder or stop, *d'*, upon the inner end of the section C, which shoulders are fitted into longitudinal grooves formed in the sections A, B, as shown in figs. 2 and 3. The shoulder *d* will abut against a stop, *e*, on the end of the section A, and prevent section B from being drawn entirely out of A, and the shoulder *d'* will abut against a stop, *e'*, on section B, and prevent section C from being entirely drawn out of the section B. The grooves *e f*, in the hollow sections, may be made as shown in figs. 3 and 4, by forming offsets on said sections, thus allowing the sections to be fitted snugly together, and providing channels or grooves for the shoulders to work in, without materially increasing the size of the sections laterally.

I am aware that telescopic or extensible shafts, each composed of two sections only, have been heretofore employed as connecting-shafts in harvesters having hinged platforms, or hinged finger-bars without platform-attachments, and therefore I do not claim such shaft as my invention.

What I claim as my invention, and desire to secure by Letters Patent, is—

A shaft for connecting the driving-power of a harvester with a rake or reel or other device applied upon a hinged finger-beam or platform, and to be driven, when such shaft is constructed of three or more than two longitudinally-adjustable telescopic sections, and such sections fitted together by tongues and grooves, and shoulders and stops, all substantially as and for the purpose described.

C. MOUL.
